(57) CLAIM

The ornamental design for a “light reflector for lanterns”, as shown and described.

DESCRIPTION

FIG. 1 is a front perspective view of the light reflector for lanterns, mounted on a lantern (in phantom), which lantern does not form a part of the claimed design;

FIG. 2 is a rear perspective view of the light reflector for lanterns, mounted on a lantern (in phantom), which lantern does not form a part of the claimed design;

FIG. 3 is a top view of the light reflector for lanterns;

FIG. 4 is a front view of the light reflector for lanterns;

FIG. 5 is a rear view of the light reflector for lanterns;

FIG. 6 is a right side view of the light reflector for lanterns, the left side view being a mirror image of the right side view of the light reflector for lanterns; and,

FIG. 7 is a bottom view of the light reflector for lanterns.
